UNITED STATES PATENT OFFICE

ROBERT H. YOUNGMAN AND ROBERT H. H. PIERCE, OF PITTSBURGH, PENNSYLVANIA

FLUE CONSTRUCTION FOR KILNS

Application filed September 12, 1927. Serial No. 219,136.

The invention relates to kilns and similar structures used for burning ceramic wares, a method of adjusting and controlling the burning operation therein, and particularly 5 to a construction of the bottom and flues thereof.

One object of the invention is to provide an improved bottom and flue construction in 10 kilns of the type herein contemplated, which shall be simple and easily constructed from standard materials, and which is easily adjustable to vary the effectiveness of the draft 15 exerted on the flues.

A specific object of the invention is to produce uniform heating throughout a kiln, by 20 means of a novel bottom and flue construction, which quickly creates a hot bottom condition and equal gas and heat distribution, thereby insuring uniform burning of the ware.

Another object is to provide an improved bottom and flue construction through the use 25 of which a wide temperature differential between the top and bottom of the kiln is avoided, and which prevents condensation of moisture on the ware in the bottom.

Still another object of the invention is to 30 construct the flues of such a kiln so that they are separate from the walls, thus facilitating repairs to either the walls or the flues, and rendering cleaning and adjustment of the flues easier.

Another object is to control the drawing off of the hot gases over substantially the 35 entire area of the kiln floor, around the objects being burned, so as to secure uniform operation, the storage of the hot gas beneath the floor in position to heat it, and the uniform drawing off of this stored gas at a speed 40 and at a place that will maintain uniformity, and conserve the heat of the gas.

The accompanying drawings illustrate an ordinary kiln provided with a bottom and flue construction embodying the invention.

45 Fig. 1 is a vertical section through a kiln, showing the bottom and flues; Fig. 2 is a plan view, partly in section, of the kiln shown in Fig. 1; Fig. 3 is a vertical section on line III-III of Fig. 2; Fig. 4 is an enlarged view 50 of a portion of the bottom and flue structure

shown in Fig. 3; and Fig. 5 is a plan view of a portion of the floor.

The invention is particularly applicable to down-draft kilns, but it is not limited thereto, as it might be applied to up-draft 55 kilns. It is particularly difficult to secure uniform heating throughout the down-draft 60 periodic kilns now in use, and generally there is a wide variation in temperature between the top and bottom thereof during firing. In 65 order to equalize the heat in a kiln it is desirable to have what is termed in the art a "hot bottom"; but with kilns of the usual construction the gases pass through the firing 70 chamber and directly to the flues and stack 75 and this condition is not readily attained. Also, in these prior kilns, cleaning of the flues is not easy, the damper control is not sufficiently flexible, and in certain types repairing is complicated by integral construction 80 of walls and flues. Furthermore, owing 85 to the lack of even heat distribution and cooler bottom region, moisture driven off from the ware in the upper portions may condense on the ware in the bottom during the 90 first stages of burning. This causes uneven finish of the charge.

The present invention overcomes all these 95 difficulties and presents additional advantages which will hereinafter be indicated. It 80 comprises the use of an ordinary riddle tile bottom permitting draw-off of hot gas over substantially the entire floor area, of a flue system consisting of an upper regulating flue 85 therebelow and a lower stack-communicating flue, separated from the upper flue by movable tiles which act as dampers and which thus make it possible to increase or decrease the resistance to flow of gases from the furnace to the stack. When these damper tiles 90 are properly set to give sufficiently restricted and properly distributed openings, a large part of the gases passing through the riddle tiles are forced to change direction and spread throughout the regulating or retarding flues before entering the lower flue. This construction slows up the outflow of gases, and by retaining them in the regulating flues somewhat before allowing them to pass to the 95 stack, further opportunity is given for ab-

straction of an additional amount of heat, creating the desired hot bottom condition. Another effect is to equalize the passage of hot gas through the kiln.

5 Referring to the drawings, the illustrative embodiment shown comprises a kiln structure composed generally of side walls 1, end walls 2, an arched roof 3, fire boxes 4, a stack 5 and stack bus conduit 6, together with suitable door openings 7, all providing a burning chamber 8. Peepholes 9 may be provided through the walls for observation of conditions in the chamber, and peepholes 9a for observation of the flues. This structure 15 is built from standard structural and refractory materials as used generally in periodic brick kilns, the details and design being familiar to all those skilled in this art.

In constructing the kiln according to the 20 invention, it is preferably built up from a concrete foundation. In order to protect this foundation from the action of the hot gases and to increase the thermal efficiency of the kiln, a refractory and insulating covering is laid on the foundation below the 25 chamber. A satisfactory construction has been found to comprise three courses of fire brick 11 laid on concrete base 10, followed by a layer of insulating brick 12, on which is 30 laid a top course of highly refractory brick 13.

According to the invention, the flue system 35 comprises upper collecting and regulating flues or retarding spaces (20) directly beneath the floor of the chamber, and communicating with lower draft or draw-off flues (19) which open into the stack bus conduit. This structure is preferably built up by erecting a plurality of walls or piers 14 longitudinally 40 of the kiln, each continuous throughout its length, and extending to stack conduit 6 at one end, thus providing a plurality of channels 15, the sides of which form the walls of the upper and lower flues. Similar piers 14a 45 are provided in the bays formed between the fire boxes, the cross channels thus formed opening into the adjacent longitudinal channels.

The construction of these piers is shown 50 on an enlarged scale in Fig. 4. They may be built from suitable brick capable of withstanding the action of the hot gases, and are built up to form the lower flues, to a height sufficient to properly carry off the waste gases, 55 this being usually adjusted to the area of the stack conduit 6. At this point two successively wider projecting courses, 16 and 17 are laid, bricks 17 forming supporting shelves on each side of each column, followed by 60 smaller brick again, and finally a top course consisting of an inverted T-shape brick. The extended edges of bricks 17 provide ledges upon which are freely laid flat tiles 18, thus 65 dividing channels 15 into lower stack-communicating flues 19 and upper regulating

flues 20. The floor of the kiln consists of riddle tiles 21 positioned between the tops of columns 14 and having their upper sides flush with the column tops. These tiles are rectangular and have on one side vertical lugs 22, so that when they are laid side by side in contact there is a space between them for passage of the gases into the upper flues. These riddle tiles rest on the shoulders of the inverted T-brick forming the tops of the piers, as shown in Figs. 4 and 5.

The tiles 18 rest freely on the projections 17 from the flue walls and they may be moved closer together or farther apart, in order to decrease or to increase the size of opening 18 between the upper and lower flues, and for this reason they may be conveniently referred to as draft-regulating or damper tiles. In general the total opening between the riddle tiles will be considerably in excess of that necessary, and the flow of gases is governed, not by the riddle openings in the floor, but by the openings between the damper tile beneath flues 20. Dampers 23 may also be set in the ends of the lower draft flues 19, in 90 order to regulate draw-off to the stack during burning.

In operation of the kiln the ware is stacked on the kiln floor in the usual manner, and after sealing off the doors and other openings, firing is commenced. The hot gases pass upwardly from the fire boxes into the kiln and are deflected from the roof uniformly through the ware, passing into the regulating flues 20 through the riddle openings. In 100 order to pass into the lower flues 19, the gases must spread and flow through the regulating flues 20 until they reach the openings between the damper tile, when they move down into the lower flues and out into the 105 stack.

This construction has two main effects. First, the use of the damper tiles 18 retards flow of the waste gases from the kiln, and by holding the gas under the floor, a hot 110 bottom condition is quickly created. Due to this retardation of gas removal resulting in more uniform draw-off over the entire floor area, better diffusion in the kiln itself is secured. Both these factors combined to secure 115 greater efficiency, and the result is that the kiln quickly reaches a uniform condition of temperature distribution, which does not vary greatly from top to bottom, and moisture condensation on the bottom ware is substantially 120 avoided. Actual practice with a kiln constructed according to the invention has demonstrated that the temperature in the ware chamber is remarkably uniform, all parts being within 1 or 2 cones, and temperature in the regulating flue is about 6 cones below that in the ware chamber.

This flue system may be applied to old 125 kilns, by rebuilding the bottom and adapting the stack outlet to receive the lower flues.

It is likewise applicable to other types of kilns, such as square or round, without any material change. All these forms are similar in construction and operation, and since the invention does not include the chamber or wall structure, it is unnecessary to illustrate those forms.

In general it is preferred to fire with gas, but any other suitable fuel, such as oil or coal, may be used.

Thus the invention provides a readily constructed kiln bottom and flue system, applicable to both new and old structures, which is easily adjustable to closely regulate the burning operation so as to secure close uniformity of heat distribution in the kiln, to keep the moisture driven from the ware above the condensation point, and to overcome the other disadvantages of the kiln flue systems heretofore used. The uniform heating secured in kilns constructed according to the invention especially adapts them for burning wares at very high temperatures. The rapid and uniform heat distribution secured by the practice of the invention insures considerable heat economy, because more of the heat supplied to the kiln is utilized in the burning than has been the case with prior constructions, and forcing the kiln to equalize burning in the later stages is rendered unnecessary, because all the ware burns uniformly in the new kiln. Furthermore, the high heat absorption in the burning chamber reduces the temperature in the lower flues and in the stack, and this in turn increases the life of the flues and stack. The life of the kiln chamber itself is also increased, inasmuch as the uniform heating produced eliminates local overheating with its consequent rapid deteriorating action. Furthermore, the individual damper tile and riddle tile remain loose and are easily removable and replaceable for cleaning of the flues whenever this may be necessary.

The invention is not narrowly limited to the structure disclosed herein, as this is given merely for purpose of illustration, and variations falling within the scope of the invention and securing the desired uniform heat distribution and controlled gas flow are within the skill of those familiar with this art.

We claim:

1. The combination in a kiln for firing ceramic ware, of a floor comprising riddle tiles supported on a plurality of intermediate piers, the sides of said piers forming the walls of a flue system comprising upper regulating flues disposed below the floor and lower stack-communicating flues, said upper and lower flues being separated by tiles adjustably disposed therebetween and adapted to act as dampers to cause the waste gases to spread through and be retarded in the regulating flues below the floor before passing to the stack flues.

2. A flue system for use with kilns adapted to avoid a wide temperature differential in the kiln, comprising a plurality of channels disposed beneath the floor of a kiln, each divided into upper regulating flues and lower stack-communicating flues by damper tiles disposed in said channels, said tiles being adjustable to vary the openings therebetween, whereby to govern the flow of gases from the kiln and to cause the waste gases to spread through the upper flue and uniformly heat the floor of the kiln.

3. A kiln having fire boxes and an exhaust stack for burning bricks and like products, comprising a floor structure made up of a series of transverse piers leading to a bus stack flue at one end, riddle tiles supported on and between said piers and completing the floor surface and providing outlets between adjacent tiles for escape of gases of combustion, damper tiles dividing horizontally the space between said piers a material distance below said riddle tiles whereby to form retarding spaces or flues just beneath the riddle tiles, said damper tiles being slidably supported by ledges formed on the sides of the piers, the space below said damper tiles forming secondary retarding flues connected to a stack flue, and adjustable dampers controlling said secondary flues at their connection to the stack flue.

4. The combination with a kiln for firing ceramic wares, of a floor adapted for passage of the waste gases, a plurality of flues disposed beneath said floor, and adjustable means provided between said flues for retarding the passage of the gases therebetween and to cause them to spread out beneath the floor, whereby the ware in the kiln is uniformly heated throughout.

5. A kiln having fire boxes and an exhaust stack for burning bricks and like products, comprising a floor structure made up of a series of transverse piers forming passages leading to a bus stack flue at one end, riddle tiles supported on and between said piers completing the floor surface therebetween and providing outlets therethrough for escape of gases of combustion, damper tiles dividing horizontally the space between said piers below said riddle tiles, said damper tiles being slidably mounted, the space below said damper tiles forming secondary flues connected to the stack flue, and adjustable dampers controlling said secondary flues at their connection to the stack flue.

6. A kiln comprising fire boxes and an exhaust stack for burning bricks and like products, comprising a floor structure made up of a series of transverse piers forming passages leading to a bus stack flue at one end, riddle tiles completing the floor surface above said passages and providing outlets therethrough for escape of gases of combustion, slidably mounted damper tiles dividing hori-

- zontally the space between said piers below said riddle tiles, the spaces below said damper tiles forming secondary flues connected to the stack flue, and adjustable dampers controlling said secondary flues at their connection to the stack flue.
7. A kiln for burning bricks and like products having a floor structure made up of a series of transverse piers leading to a bus stack flue at one end, riddle tiles completing the floor surface between said piers and providing outlets therethrough for escape of gases of combustoin, adjustable dampers horizontally dividing the space between said piers below said riddle tiles, said dampers being adapted to control flow of gas from the kiln, the space below said dampers forming secondary flues and being connected to the stack flue, and adjustable dampers controlling said secondary flues at their connection to the stack flue, whereby to regulate draw-off of gases through the kiln floor, and to hold hot gas in the floor structure.
8. A kiln for firing ceramic ware comprising walls, a roof, firing boxes, a refractory base for said kiln, a plurality of heat resisting piers erected on said base and forming channels through it, ledges formed on said piers, damper tiles slidably resting on said ledges and dividing said channels into upper and lower flues, stack connections to said lower flues, and a floor comprising riddle tiles having projections on the sides thereof to provide gas passages therebetween supported on said piers, said damper tiles being adjustable to control the openings therebetween, whereby to cause the waste gases to spread under and be retaining in heating relation to the floor.
9. The combination with a kiln for firing ceramic wares, of a floor adapted to permit passage of hot gases therethrough throughout its area, flues beneath the floor for collecting said gas, draw-off flues below said first mentioned flues, and movable means positioned between said upper and lower flues whereby the flow of gases from the upper flues to the lower flues may be regulated as to rate and place.
10. The combination with a kiln of the class described, of a floor adapted to permit down-flow of gas throughout its area, collecting flues beneath said floors adapted to store hot gases below the floor, exhaust flues under the floor and co-extensive with the said collecting flues, and movable means between said collecting and exhaust flues adapted to control the rate and place of flow of gas therebetween.
11. In a kiln of the class described, the combination of a floor perforated to permit down-flow of gas throughout its area, collecting and regulating flues beneath the floor adapted to receive and store the hot gases under the floor, parallel co-extensive draw-

off flues beneath the collecting flues and connected to an exhaust flue or stack, slidable floor members separating the said collecting and draw-off flues, said slidable floor members being normally spaced apart and movable to regulate the spaces between them, whereby to control the rate and place of passage of gas from the collecting to the draw-off flues.

In testimony whereof, we hereunto sign our names.

ROBERT H. YOUNGMAN.
ROBERT H. H. PIERCE.
